UNITED STATES PATENT OFFICE.

CHARLES A. BAILEY, OF CROMWELL, CONNECTICUT.

DESIGN FOR A TOY SAFE.

SPECIFICATION forming part of Design No. 25,577, dated June 2, 1896.

Application filed April 30, 1896. Serial No. 589,786. Term of patent 7 years.

To all whom it may concern:

Be it known that I, CHARLES A. BAILEY, a citizen of the United States, residing at Cromwell, in the county of Middlesex and State of Connecticut, have invented and produced a new and original Design for Toy Safes, of which the following is a specification, reference being had to the accompanying drawings, illustrating the same, in which—

10 Figure 1 is a plan view of the front of the bank; Fig. 2, a view of one side; Fig. 3, a view of the back; Fig. 4, a view of the other side, and Fig. 5 a view of the top of the bank.

This invention has relation to a certain 15 new and original design for toy banks; and it consists in the novel configuration of parts, as hereinafter described, and illustrated in the accompanying drawings.

Referring to the drawings, the front or 20 door A of the bank is designed with an ornamental panel *a* and a vine figure *a'* at the top, bottom, and rear edge of said panel.

The sides, Figs. 2 and 4, are ornamented

alike with an open-work design comprising a central four-leafed figure *b*, as shown, surrounded by an ornamental ring *b'*, from which points *b''* run to the sides, top, and bottom of the panel, in the four corners of which are ornamental scrolls *b'''*.

The back panel C of the bank is ornamented 30 with a design similar to that of the sides, except that a slot *c* for the reception or passage of the money into the bank extends across its upper end.

The top D of the bank is ornamented by a 35 central flower figure *d*, surrounded by a ring *d'*, the latter being encircled by open ornamental scrolls *d''*, with a star figure *d'''* at each of the four corners of the top.

What I claim is—

40 The design for a toy bank substantially as herein shown and described.

CHAS. A. BAILEY.
